UNITED STATES PATENT OFFICE.

CHARLES WEIR CRANKSHAW, OF ATLANTA, GEORGIA.

DESIGN FOR A MEDAL.

SPECIFICATION forming part of Design No. 32,303, dated March 6, 1900.

Application filed November 29, 1899. Serial No. 738,730. Term of patent 7 years.

To all whom it may concern:

Be it known that I, CHARLES WEIR CRANKSHAW, a citizen of the United States, residing at Atlanta, in the county of Fulton and State of Georgia, have invented and produced a new and original Design for a Medal, of which the following is a specification, reference being had to the accompanying drawings, forming part thereof.

Figure 1 is a plan front view of medal and suspending-bar, showing my new design. Fig. 2 is a plan back view of medal and bar.

The leading and material features of entire design made up of cross, wreath on each side in relief, as shown, and the battle-flag, also

in relief; inside wreath on back of medal, as set out above and shown in the drawings attached, is my new and original design.

Having described my invention, what I claim as new, and desire to secure by Letters Patent, is—

The design for a medal, as herein shown and described.

In testimony whereof I have signed my name to this specification in the presence of two subscribing witnesses.

CHARLES WEIR CRANKSHAW.
